CUTTING TOOL

George J. Barrett and Sosthene Robichaux,
Houston, Tex.

Application November 16, 1939, Serial No. 304,668

21 Claims. (Cl. 164—0.8)

This invention relates to a cutting tool and has particular relation to that type of cutting tool specially designed for cutting through a casing or pipe set in a well bore and for completely removing a section of said casing or pipe.

It is another object of the invention to provide a cutting tool of the character described having a plurality of series of knives or cutters arranged to be brought into cutting relation with the pipe to be removed in succession so that when the knives of one series become worn out the knives of another series may be applied to the work and the cutting operation thus continued without substantial interruption until the section to be cut out has been removed.

It is another object of the invention to provide novel means for retracting the knives of one series when it is desired to bring the knives of another series into action.

Another object of the invention is to provide, in a cutting tool, novel means for bringing the cutters into action.

The invention herein disclosed constitutes certain improvements over that type of cutting tool disclosed in our co-pending application, Serial No. 208,362, filed May 17, 1938, which matured into Patent No. 2,199,020, dated April 30, 1940.

With the above and other objects in view the invention has particular relation to certain novel features of construction, operation and arrangement of parts, examples of which are given in this specification and illustrated in the accompanying drawings, wherein—

Figure 1 shows a fragmentary, side elevation of the cutting tool, partly in section, showing the cutting knives retracted.

Figure 2 shows a vertical, sectional view showing the tool in action.

Figure 3 shows a vertical, sectional view showing the tool in position to retract a worn set of knives and to bring the next succeeding set into action.

Figure 4 shows a cross-sectional view taken on the line 4—4 of Figure 1.

Figure 5 shows a fragmentary, plan view of a series of cutters.

Figure 6 shows a cross-sectional view taken on the line 6—6 of Figure 1.

Figure 7 shows a vertical, sectional view of another embodiment of the invention showing the knives in inactive position.

Figure 8 shows a similar view of said embodiment showing the knives in active position, and

Figure 9 shows a cross-sectional view taken on the line 9—9 of Figure 8.

Referring now more particularly to the drawings wherein like numerals of reference designate the same parts in each of the figures, the numeral 1 designates a tubular operating string such as a drill stem which extends to the ground surface and to the lower end of which the tubular coupling 2 is connected. Within the lower end of the drill stem there is a cylinder 3 whose lower end has an external, annular flange 4 which is threaded into the box at the upper end of said coupling and which is clamped in said box by means of the threaded pin on the lower end of the drill stem 1 whereby the cylinder is anchored securely in place. There is a mandrel 5 whose upper end is formed with a plunger 6 adapted to work in said cylinder. The lower end of the mandrel is reduced and downwardly tapered forming an expander 7 whose lower end terminates in a downwardly extended guide rod 8.

There is a series of similar tubular cutter heads 9, 10, 11 which are detachably connected together and the upper one of which is detachably connected to the lower end of the coupling 2. Connected to the lower end of the lower head 11, by the coupling 12, there is a pipe 13 which is extended any selected distance beneath. Each head has the radial blade slots 14 extended therethrough whose lower sides decline outwardly. The cutter blades 15 work through said slots. The heads have the external lugs 16 which bear against the rear sides of the blades or cutters to reinforce them during operation as more clearly shown in Figure 8.

As more clearly shown in Figure 5 the inner ends of the respective blades or cutters are widened and inwardly beveled so as to fit closely together when the cutters are retracted. The cutters of a series are normally held retracted by means of an elastic band 17, forming a tie, which passes through the eyes 18 of the cutters. The series of cutters have the vertically aligned central bearings 19 to receive the guide rod 8 and expander 7 as shown in Figures 1, 2 and 3.

Each head has a removable wear ring as 20 driven therein and formed of suitable wear resisting material positioned to support the inner ends of the cutters when the cutters are in active position. The blades or cutters have the transverse pins 21 as more accurately shown in Figures 1 and 6 to limit their outward movement. The blades of each series will be normally supported by the corresponding wear ring and maintained in radial, horizontal, position by means of the corresponding tie 17.

The tool may be assembled as shown in Figure 1 and let down into the casing to be cut. However, before lowering the tool it is preferable to cut out a short section of the casing by another type of cutting tool, for example, such as that shown in our copending application above referred to. When the tool has been lowered into the position shown in Figure 1, fluid under pressure may be exerted by a pump at the ground surface against the upper end of the plunger 6, forcing the mandrel 5 and expander 1 downwardly until the external annular shoulder 22 on the mandrel, formed by the reduction of the lower end thereof, engages the inner end of the upper series of cutters 15. The cutters will thus be forced outwardly into the position shown in Figure 2 and the plunger 6 will have moved into position beneath the cylinder 3 thus relieving the pump pressure and indicating to the operator that the upper series of cutters 15 are in extended or cutting position. The tool may then be lowered until the cutters come into contact with the upper end of the lower section of the casing 23 as indicated in Figure 2 and as the tool is thereafter rotated the cutters will ride on and gradually cut away the upper end of the lower section of casing until the cutters have become dulled or completely worn away. The weight of the operating stem 1 on the cutters may be regulated as desired to give the desired result.

When the upper series of cutters have been worn out, the pump may be stopped and the cutting tool may be elevated into the position shown in Figure 3, the outer ends of said cutters engaging against the lower end of the upper section of the casing. Upon such engagement the inner ends of the cutters will be moved upwardly and outwardly, the ties 17 yielding to permit this, until said tie comes into contact with and is severed by the blade 24 on the inner side of the head 3 whereupon the outer ends of the cutters will drop into inactive position so as not to engage against and hang on the inside wall of the casing during the subsequent operation of the tool. This elevation of the tool will carry the next succeeding series of cutters beneath opposite the cut away portion of the casing and the pump may be again started forcing the mandrel 5 and expander 1 further downwardly and expanding this next succeeding series of cutters into position to operate on the upper end of the lower section of casing and the tool may then be lowered until said cutters are in contact with said upper end and then rotated and the cutting operation proceeded with as before until said cutters are dulled or worn away and the tool may be elevated as before and the next succeeding series of cutters brought into action as hereinabove explained until the cut is completed. Only three series of cutters are shown in the present illustration although any number of series desired may be employed.

It is stated above that the initial cut through the casing should be made by another type of cutting tool before lowering the type of tool herein disclosed into the casing to proceed with the work. It is not absolutely necessary that said initial cut be made before lowering the present type of tool into the casing. If it is desired the present type of tool may be lowered to the point where the cut is to be made. When it has reached the desired point where the cut is to be made, fluid under pressure may be applied to the plunger 6 and the upper series of cutters expanded into contact with the inside of the casing

and the tool rotated until the casing has been severed, whereupon the plunger 6 and mandrel 5 will move on down to fully expand the upper series of cutters into the position shown in Figure 2 and the cutting operation may then be proceeded with and the series of cutters beneath may be brought into action successively from above downwardly as the cutters of the preceding series are dulled or worn away.

In the embodiment illustrated in Figures 7 to 9 there is an assembly of tubular cutter heads 25, 26, 27, detachably secured together and the upper one of which is detachably secured to the coupling 2. These cutter heads have the radial slots 28 whose lower sides decline outwardly and pivotally mounted in these slots are the cutters 29 having the inward extensions 30 which project inwardly beyond the pivots. Arranged axially within the head assembly there is the mandrel 31 whose lower end is supported on a coil spring 32 which is inclosed within the lower head 27 and which is supported on the plug 33 which is screwed into the lower end of the head 27. The lower end of the head 27 has the vertical channels 34 leading downwardly therethrough for the passage of an operating fluid, such as water, downwardly into the casing to maintain circulation during the cutting operation.

Secured within the upper end of the head 25 there is a cylinder 35. The mandrel 31 has the upper, intermediate, and lower heads 36, 37 and 38 arranged to engage above the inner extensions 30 as shown in Figures 7 and 8. When the cutters are in retracted position as shown in Figure 3, the head 36 will engage against and close the lower end of the cylinder 35. Before lowering this type of cutter into the well, a section of the casing should be cut away, as illustrated in Figure 7, by another type of tool, such, for example, as that disclosed in our co-pending application above referred to. The cutter may then be lowered into the well into the position shown in Figure 7 with the cutters opposite the cutout portion of the casing. Fluid under pressure, may then be forced by a pump at the ground surface down through the drill stem and cylinder 35 thus forcing the mandrel 31 downwardly and expanding the cutters into the position shown in Figure 8. The drill stem may then be let down until the lower series of cutters are in contact with the upper end of the lower section of the casing and the tool may be rotated thus cutting away said lower section and this operation may continue until the operative portions of the lower series of cutters are entirely worn away thus allowing said cutters to enter the casing and the tool may then be lowered into the position shown in Figure 8 until the next succeeding series of cutters above engage the upper end of the lower section of casing. In Figure 8 this series of cutters is shown in action with the cutters partially worn away. When the operative ends of these cutters are completely worn away the tool may be further lowered until the upper series of cutters come into contact with the casing and the work proceeded with as before until all of the series of cutters are worn away or the cut completed whereupon on elevation of the tool the spring 32 will operate to elevate the mandrel 31 and retract the cutters into the position shown in Figure 7 and the tool may then be withdrawn from the well.

The drawings and description are illustrative merely while the broad principle of the invention will be defined by the appended claims.

What we claim is:

1. A cutting tool adapted to cut by rotation and shaped to enter a pipe in a well and comprising a plurality of longitudinally spaced cutting means, each of said cutting means having an effective cutting diameter greater than the diameter of the pipe being cut and means to bring said cutting means successively into cutting relation with the end of a well pipe beneath whereby said pipe will be cut away from above 10 downwardly as the tool is fed downwardly.
2. A cutting tool adapted to cut by rotation and shaped to enter a pipe in a well and comprising cutting means spaced apart vertically and means effective to successively engage and actuate the cutting means outwardly into cutting position relative to the upper end of the well pipe to operate on said end in succession as the tool is fed downwardly.
3. A cutting tool shaped to enter a pipe in a well and comprising cutting means spaced apart vertically and movable outwardly into cutting position relative to the upper end of a lower cut off section of the well pipe, means for actuating the cutting means, in succession, from above downwardly, into cutting relation with said upper end.
4. A cutting tool adapted to cut by rotation and shaped to enter a pipe in a well and comprising a head assembly, a plurality of cutting means thereon movable inwardly into inactive position and outwardly into active position and means effective to successively actuate the cutting means outwardly into active, or cutting, position relative to the upper end of the well pipe to operate on said end in succession as the tool is fed downwardly.
5. A cutting tool adapted to cut by rotation and shaped to enter a pipe in a well and comprising a head assembly, a plurality of cutting means thereon movable inwardly into inactive position and outwardly into active position and means effective to successively actuate the cutting means outwardly into active, or cutting, position relative to the upper end of the well pipe to operate on said end in succession as the tool is fed downwardly and an operating string for manipulating the tool.
6. A cutting tool adapted to cut by rotation and shaped to enter a pipe in a well and comprising a head, a plurality of cutters spaced apart 50 vertically thereon and movable inwardly into inactive position and outwardly into active position into cutting relation with the upper end of a section of pipe beneath, means for actuating the cutters into active position, successively, from above downwardly whereby said upper end of said section will be completely removed by the cutters in succession as the tool is moved downwardly.
7. A cutting tool adapted to cut by rotation and shaped to enter a pipe in a well and comprising a head, a plurality of cutters spaced apart 60 vertically thereon and movable inwardly into inactive position and outwardly into active position into cutting relation with the upper end of a section of pipe beneath, means for actuating the cutters into active position, successively, from above downwardly whereby said upper end of said section will be completely removed by the cutters in succession as the tool is moved downwardly, said cutters, when in active position, being retractable to inactive position by the lower end of the section of well pipe above, upon upward movement of the tool.
8. In a pipe cutting tool a head, a series of 75
- radial cutters thereon, a continuous elastic band connecting the cutters of the series and normally maintaining them in inactive position and means for moving the cutters of the series outwardly into active position.
9. In a pipe cutting tool a head, a series of radial cutters thereon, an elastic tie member connecting the cutters of the series and normally maintaining them in inactive position and means operable against the inner ends of the cutters of the series and arranged to be operated by an operating fluid under pressure and effective to move the cutters outwardly into active position, said cutters, when in active position, being retractable by the lower end of the section of the well pipe above, upon upward movement of the tool and means in the tool for severing the tie member upon such retraction of the cutters.
10. A cutting tool adapted to cut by rotation and shaped to enter a pipe in a well and comprising a head assembly, cutting means thereon spaced apart vertically and each having an effective cutter diameter greater than the diameter of the well pipe, and means arranged to be operated by fluid under pressure and effective to bring said cutting means successively into cutting relation with the end of a well pipe beneath whereby said pipe will be cut away from above 20 downwardly as the tool is fed downwardly.
11. A cutting tool adapted to cut by rotation and shaped to enter a pipe in a well and comprising a head assembly, a plurality of cutting means thereon movable inwardly into inactive position and outwardly into active position and means arranged to be operated by fluid under pressure and effective to successively actuate the cutting means outwardly into active, or cutting, position, relative to an end of the well pipe to operate on said end in succession as the tool is moved longitudinally relative to the pipe.
12. A cutting tool adapted to cut by rotation and shaped to enter a pipe in a well and comprising a head assembly, a plurality of cutting means thereon movable inwardly into inactive position and outwardly into active position and means arranged to be operated by fluid under pressure and including means to successively engage with the cutting means to actuate the cutting means outwardly into active, or cutting, position, relative to the upper end of the well pipe to operate on said end in succession as the tool is fed downwardly, said cutters, when in active position, being mounted to be released from the actuating means and retractable to inactive position by the lower end of the section of the well pipe above upon upward movement of the tool.
13. A cutting tool adapted to cut by rotation and shaped to enter a pipe in a well and comprising a plurality of longitudinally spaced cutting means, each of said cutting means having an effective cutting diameter greater than the diameter of the pipe being cut, and means operatively connected with the cutting means and effective to bring said cutting means successively into cutting relation with the end of a well pipe beneath whereby said pipe will be cut away from above 30 downwardly as the tool is fed downwardly.
14. A cutting tool adapted to cut by rotation and shaped to enter a pipe in a well and comprising a plurality of longitudinally spaced cutters, means effective to actuate a predetermined number of cutters independently of the other cutters into active or cutting position relative to the well pipe.
15. A cutting tool adapted to cut by rotation

and shaped to enter a pipe in a well and comprising a plurality of cutters spaced longitudinally apart on the tool, means for actuating the cutters into active or cutting position, said cutters being arranged to limit movement of the actuating means whereby a predetermined number of cutters are actuated simultaneously, said cutters being mounted to release the actuating means by the lower end of the section of the well pipe above upon upward movement of the tool.

16. A cutting tool adapted to cut by rotation and shaped to enter a pipe in a well and comprising a plurality of cutters spaced longitudinally apart on the tool, means for actuating the cutters into active or cutting position, said cutters being arranged to limit movement of the actuating means whereby a predetermined number of cutters are actuated simultaneously, said cutters being mounted to release the actuating means to allow more cutters to be actuated by the actuating means and be retracted to inactive position by the lower end of the section of the well pipe above upon upward movement of the tool.

17. A cutting tool adapted to cut by rotation and shaped to enter a pipe in a well and comprising a cutter support, cutters spaced apart vertically on the support and movable into active and inactive positions, each cutter being of a length to extend out radially to the outside of the pipe to be cut when said cutter is in active position to completely remove a section of the pipe upon rotation of the tool and means for bringing the cutters into active position successively whereby a cutter will continue the work of the preceding cutter upon the lowering and rotation of the tool.

18. A cutting tool adapted to cut by rotation and shaped to enter a pipe in a well and comprising a cutter support, cutters spaced apart vertically on the support and movable into active and inactive positions, each cutter being of a length to extend out radially to the outside of the pipe to be cut when the cutter is in active position so as to completely remove a section of the pipe upon rotation of the tool and means for

bringing the cutters into active position whereby a cutter will continue the work of the preceding cutter upon the lowering and rotation of the tool.

19. A cutting tool adapted to cut by rotation and shaped to enter a pipe in a well and comprising a cutter support, series of cutters spaced apart vertically on the support and movable into active and inactive positions, the cutters of each series being of a length to extend out radially to the outside of the pipe to be cut when the cutters of the series are in active position so as to completely remove a section of the pipe upon rotation of the tool and means for bringing the respective series of cutters into active position successively whereby a series of cutters will continue the work of the preceding series upon the lowering and rotation of the tool.

20. A cutting tool adapted to cut by rotation and shaped to enter a pipe in a well and comprising a cutter support, series of cutters spaced apart vertically on the support and movable into active and inactive positions, the cutters of each series being of a length to extend out radially to the outside of the pipe to be cut when the cutters of the series are in active position so as to completely remove a section of the pipe upon rotation of the tool and hydraulically operable means for bringing the respective series of cutters into active position whereby a series of cutters will continue the work of the preceding series upon the lowering and rotation of the tool.

21. A cutting tool adapted to cut by rotation and shaped to enter a pipe in a well and comprising a cutter support, series of cutters spaced apart vertically on the support and movable into active and inactive positions, the cutters of each series being of a length to extend out radially to the outside of the pipe to be cut when the cutters of said series are in active position so as to completely remove a section of pipe upon rotation of the tool and means for bringing the series of cutters into active position whereby a series of cutters will continue the work of the preceding series upon the lowering and rotation of the tool.
